UNITED STATES PATENT OFFICE.

RICHARD H. RICE, OF LYNN, MASSACHUSETTS, ASSIGNOR TO GENERAL ELECTRIC COMPANY, A CORPORATION OF NEW YORK.

AUTOMATIC REGULATOR FOR MOTOR-DRIVEN PUMPING APPARATUS.

1,100,257.

Specification of Letters Patent. Patented June 16, 1914.

Application filed May 19, 1910. Serial No. 562,172.

To all whom it may concern:

Be it known that I, RICHARD H. RICE, a citizen of the United States, residing at Lynn, county of Essex, State of Massachusetts, have invented certain new and useful Improvements in Automatic Regulators for Motor-Driven Pumping Apparatus, of which the following is a specification.

This invention relates to improvements in automatic regulating devices for motors or prime movers such as steam engines, turbines, etc., said devices being responsive to changes in the pressure of a fluid which is being transferred by a pump driven by said motor with the object of maintaining the suction or suction pressure constant.

It is especially designed for use in connection with coking ovens, where the gas resulting from the coking operations is led off to be utilized for industrial purposes.

When coal is highly heated in a closed retort out of contact with air, it undergoes a complete change and yields a great variety and quantity of gas, liquids, and solid volatile products, together with a non-volatile residue of coke. The gas and other volatile products escape from the retort through a pipe, and when the distillation of the coal is at an end, the coke, consisting of impure carbon mixed with ash or mineral matter, can be drawn out from the retort. The hot gas passing through the pipe is led into sundry pieces of apparatus which purify and condense and cool it, after which it is forced by the compressor or pump into a suitable gas holder from which it is distributed for illuminating and heating purposes. The suction of the compressor produces a draft upon the retorts, and inasmuch as the volume of gas generated is not constant, it follows that the speed of the compressor must be varied to accord with the amount of gas given off by the retorts in order to hold a constant suction in the pipe where it leaves the retorts or the coke ovens.

The ordinary mode of regulating the speed of the turbine or other motor driving the compressor or exhauster is to station an observer at the retorts who by means of a suitable gage notes when the pressure in the

main increases or decreases and thereupon telephones to the engineer in charge of the compressor plant which is usually located at some distance away. The engineer manually regulates the speed of his engine or motor in accordance with these messages from the observer, in order to maintain as closely as possible an even suction upon the main. But this system is obviously uncertain, owing to the necessity of depending on two or more operators, who must be always on the watch and must keep in almost constant communication with each other. The object of the present invention is to better these unsatisfactory conditions by substituting an automatic mechanism for the observer and his fellow operator, such mechanism comprising broadly speaking a pressure responsive device in the main near the retorts, acting by means of a suitable transmission on the controlling mechanism of the engine or motor.

The novel features of my improved apparatus are set forth in the accompanying description and claims.

In the accompanying drawings, Figure 1 is a diagrammatic view of a system embodying my invention; Fig. 2 is a plan view of the levers connected to the pressure regulator; Fig. 3 is a side elevation, partly in section, showing the solenoid magnets and gear which control the valves of a turbine; Fig. 4 is a plan view of the same; and Figs. 5 and 6 illustrate a valve operating mechanism with the regulating system connected to it.

The gas generator or retort 1 delivers its products to a series of treating devices (not shown) arranged between the T 7 and the compressor 3 and connected by the main or pipe 2 to said compressor. The compressor or exhauster 3 is preferably a centrifugal compressor, although the machine can be of the reciprocating type. This compressor is driven by a suitable motor, preferably a steam turbine 4 of the Curtis type, although an electric motor or reciprocating engine might be used. The turbine is provided with a valve operating mechanism 5, Figs. 5 and 6, controlled by a speed responsive device, and actuating a plurality of successively

operated valves which are also under the control of a pressure responsive device located near the gas generator.

The pressure responsive device consists of a water receptacle 6 mounted on the T connection 7, closely adjacent to the retort 1. A bell 8 is located in the receptacle 6 and connected to the lever 9 by means of a bifurcated rod 10. The rod 10 projects through a hole 11 formed in the cover 12. Threaded into the receptacle 6 is a vertical tube 14 which extends upwardly through the water or other suitable liquid 15 and terminates within the bell 8. This tube allows the gases from the T 7 to pass into the bell. The water serves as a seal to retain the gases in said bell while permitting it to move vertically in either direction. The pressure responsive device is designed to coöperate with the pump driving motor regulator to maintain a constant suction pressure of from 2" to 3" of water, as required, and hold it at a value not exceeding 1/10" to .05" either way from the mean.

The bifurcated portion of the rod 10 is provided with a pin which coöperates with the bifurcated end of the lever 9 and imparts to said lever any movement of the bell 8, which bell is balanced by a counterweight 16 held in position by a suitable set screw. On the lever 9 is a projection 17 which serves as a switch and coöperates with the contact screws 18 and 19 located in an open frame 20 forming part of the lever 21. The contact screws are threaded into insulating bushings 22 and 23 which are driven into the upper and lower members of the frame 20. The levers 9 and 21 are pivotally mounted on a shaft 24 which in turn is mounted in the brackets 13 on the cap 12 and held in fixed position by a set screw 27. The levers 9 and 21 work independently of each other and to prevent their hubs from coming in rubbing contact with each other a spacing member or collar 28 of enlarged diameter is machined on the shaft 24.

Secured to the contact members 18 and 19 are two electrical conductors 29 and 30, the other ends of which are connected to the solenoid magnets 31 and 32. Connected to the contact member 33 formed on the projection 17 of the lever 9 is a third electrical conductor 34 which is common to the magnets 31 and 32. This conductor completes their circuits and arranged therein is a battery 35 which furnishes the current for energizing the magnets 31 and 32. These magnets are provided with an armature 36 capable of operating a lever 37 in both directions. The armature 36 is slotted to receive one end of the lever 37 which is fulcrumed at 38 on the double lever 39. On the lever 37 are the pawls 40 and 41 which have only a slight movement sufficient to allow them to engage the teeth 42 of the

segmental gear 43. When the armature 36 is moved in either direction by the pull of the magnets, the lever 37 fulcrums on the shaft 38 and forces one of the pawls into engagement with the teeth 42 of the gear. When it comes in contact therewith, the lever 37 and the double lever 39 act as a unit and any further movement of the armature 36 causes the levers 37 and 39 to move about the shaft 44 carrying with them the segmental gear 43. The bridge piece 45, Fig. 4, serves as a tie for the two portions of the double lever 39. Connected to the levers 37 and 39 are the springs 46 and 47. These springs tend to retain said levers in the position shown in Fig. 3.

When the magnets 31 and 32 are energized, (as these are identical in construction, the description of one will suffice, for example the magnet 31) the first movement of the member 36 will cause the pawl 40 to come in contact with the teeth 42 of the segmental gear 43. Any further movement will cause the levers 37 and 39 to move upwardly carrying with them the gear 43. By this movement motion is communicated to the rod 48 which influences the action of the valves of the steam turbine through a system of levers. When the magnet 31 is de-energized, the springs 47 cause the levers 37 and 39 to assume a straight line relation, thereby pulling the pawl 40 away from the teeth 42 when it again assumes the position shown in Fig. 3.

When the magnet 32 is energized, the movement of the levers 37 and 39 and gear 43 is in the opposite direction, which obviously has an opposite effect on the turbine valves. When either of the magnets is energized, the movement communicated to the gear is equal to a distance corresponding to the closing or opening of one valve.

The double lever 39 serves as a switch and engages with contacts 49 and 50 which are connected to the conductors 51 and 52. These conductors are connected to the electromagnets 53 and 54, and also connected to these magnets is a common conductor 55, the other end of which is permanently connected to the lever 39. A battery 56 is provided and furnishes current to energize the magnets 53 and 54. Coöperating with said magnets is an armature 57 which controls the two-part lever 58, 59, pawls 60 and 61, and segmental gear 62. Attached to the gear 62 is a lever 63 which is connected to the lever 21 by means of a rod 64. The levers 58 and 59 are retained in their neutral position by means of the springs 65 and 66. This last or follow-up device is identical in construction with the device which operates the rod 48 that is connected to the valve operating mechanism. Said device is for the purpose of returning the lever 21 and the contacts 18 and 19 to the neutral position.

in relation to the contactor 33. For example, suppose the pressure increases in the bell 8. This necessitates the opening of more valves of the turbine, thereby increasing its speed and also that of the compressor which releases the increased pressure from the gas retort. The increased pressure causes the bell 8 and the rod 10 to move upwardly. This in turn imparts an upward movement 10 to the left end of the lever 9 and causes the contact 33 to travel downwardly into contact with the screw 19. By this movement the circuit which energizes the magnet 31 is closed. The pull of the magnet lifts the 15 armature 36, levers 37 and 39 until the lever 39 contacts with the member 49, thereby closing a second circuit and energizing the magnet 53 through the conductor 51. The pull of the magnet 53 lifts the armature 57, 20 levers 58 and 59, and gear 62. As said gear swings, it gives a downward movement to the lever 63. This downward movement of the lever imparts a similar movement to the right end of the lever 21 through the rod 64. 25 The movement of the lever 21 draws the contact 19 away from the contactor 33, thereby breaking the circuit and allowing the levers 37 and 39 to return to their neutral position.

30 The lower extremity of the rod 48 is connected to a bell crank 67 which is fulcrumed at 68, the upper arm 69 of said bell crank being connected to a floating lever 70. The upper extremity of the lever 70 is pivotally connected to a link 71. The opposite end of the link 71 is pivotally connected to the lever 72 which is mounted on the shaft 73. On the other end of the shaft 73 is a lever 74 which is connected to the speed responsive 35 device 75. By means of a suitable link 76, the lever 70 is connected to an arm 77 on the shaft 78 on which are a plurality of shield plates 79 set about the axis of the shaft in successive order. Rotation of these plates 40 79 will throw certain actuating pawls or dogs in or out of engagement with the notches in the valve stems 80. By this means the valves 81 are successively opened or closed, as the case requires. The work of 45 operating the valves is done by the lever 82 which is mounted on the shaft 78 and receives a constant oscillating movement from the connecting rod 83 which is connected to a crank or eccentric located in the 50 casing 84. The valves 81 are located in a suitable steam chest 85 from which the steam is led through the conduit 86 to the buckets on the wheel 87 and imparts a rotating movement thereto.

55 60 Gases formed in the retort pass through the treating apparatus and the pipe 2 to the centrifugal compressor 3 driven by the turbine 4 having suitable valve operating mechanism which controls a plurality of

successively operated valves. These valves 65 are controlled by the speed responsive device 75, but in case the supply of gas increases or decreases, it is desirable to bring into play the pressure regulator which automatically modifies the control of the device 75. When the pressure in the retort increases, this pressure is communicated to the bell 8 which moves upward carrying with it the rod 10 and the left end of the lever 9. The opposite end has a downward 70 movement which makes the member 33 engage the contact 19. This closes an electrical circuit, energizes the magnet 31 by the current from the battery 35 passing through 75 30 and 34, and causes the gear 43 to move 80 in the direction of the arrow. This causes a downward movement of the rod 48 which imparts motion to the bell crank 67 and gives a movement to the floating lever 70 in the direction of the arrow, pulling with it 85 the link 76, arm 77 and shields 79, which allows a pawl to come in position to open one of the valves. The arrangement of the levers 67, 69, 70 and links 71, 76 is such that the valves are always subject to the control 90 of the speed responsive device 75 but the pressure responsive device can, when necessary, act at the same time to change the position of the levers and links and the shield plates which determine the movement of the 95 valves by the lever 82, said pressure device thus acting with the device 75 to regulate the operation of the apparatus.

Simultaneously with the opening of the valve, the lever 39 comes in contact with the member 49, thus closing a circuit and energizing the magnet 53, lifting the armature 57 and causing the lever 21 to move downwardly, thereby acting as a follow-up device and breaking the contact between the members 19 and 33. If the pressure in the retort continues to increase, this operation will take place until all the valves are open. If the pressure decreases, the operation of the members will be reversed, thereby closing some or all of the valves. 100 105 110

In accordance with the provisions of the patent statutes, I have described the principle of operation of my invention, together with the apparatus which I now consider to 115 represent the best embodiment thereof; but I desire to have it understood that the apparatus shown is only illustrative and that the invention can be carried out by other means.

What I claim as new and desire to secure by Letters Patent of the United States, is,—

1. The combination with a gas generator, of a main leading from the generator, a pump for drawing gas from the generator, 125 a motor for driving the pump, means for regulating the supply of energy to the motor comprising two pivoted levers carrying

- electric contacts that are movable into and out of engagement with each other and an electromotive device connected with said contacts, a device responsive to the pressure 5 in the main that controls the movement of one lever, and a follow-up mechanism comprising contact means controlled by a movable part operated by the electromotive device aforesaid and also comprising an elec- 10 tromotive device connected therewith that controls the movement of the other lever to prevent over-travel of said regulating means.
2. The combination with a gas generator, of a pump for exhausting the gas there- 15 from that is located at some distance from said generator to the pump, a main leading from the generator, an engine which drives the pump, a device responsive to variations in the gas pressure which is located near 20 the generator and comprises a liquid receptacle and a bell arranged within the receptacle, the interior of the bell being in communication with the main, an engine regulating mechanism including an electro-motive device, electrical connections between 25 said electro-motive device and the pressure responsive device that are controlled by the movements of the bell and electromotive means controlled by the movement of a part 30 of the regulating mechanism aforesaid that is operated by said electromotive device for interrupting the connections aforesaid after they have been rendered effective by the bell.
3. The combination with a gas generator, 35 of a gas main leading therefrom, a liquid receptacle adjacent to said generator, a bell in said receptacle, a pipe communicating with the main and opening beneath said bell, electric contacts controlled by the bell, a 40 power driven pump connected to said main, and an electrical speed regulating device for said pump in circuit with said contacts.
4. The combination with a turbine, of a 45 gas pump driven thereby, a pressure responsive device on the gas main supplying the pump, an electric circuit controlled by the device, electromagnets in the circuit, a movable armature for the electromagnets, a segment gear, a lever movable adjacent 50 thereto, a double pawl pivoted on the lever and adapted to be actuated by said armature and to engage with said gear, valve-operating mechanism for the turbine, and means actuated by said gear for controlling said 55 valve-operating mechanism.
5. The combination with a turbine, of a 60 gas pump driven thereby, a pressure responsive device on the gas main supplying the pump, an electric circuit controlled by the device, electromagnets in the circuit, a movable armature for the electromagnets, a segment gear, a lever movable adjacent thereto, a double pawl pivoted on the lever and adapted to be actuated by said armature and to 65 engage with said gear, springs biasing said lever and pawl to a central position, valve-operating mechanism for the turbine, and means actuated by said gear for controlling said mechanism.
6. The combination with a turbine, of a 70 gas pump driven thereby, a pressure responsive device on the gas main supplying the pump, an electric circuit controlled by the device, electromagnets in the circuit, a movable armature for the electromagnets, a 75 segment gear, a lever movable adjacent thereto, a double pawl pivoted on the lever and adapted to be actuated by said armature and to engage with said gear, springs biasing said lever and pawl to a central position, 80 valve-operating mechanism for the turbine, means actuated by said gear for controlling said mechanism, and a follow-up device for said mechanism which operates by breaking said circuit. 85
7. The combination with a gas generator, of a gas main leading from the generator, a pump connected thereto at a distance from the generator, a turbine driving the pump and provided with a plurality of successively 90 operating valves, an electrical device for controlling the operation of said valves, a pressure responsive device at the generator end of said main, an electric circuit having contacts operated by the pressure responsive 95 device and including also the valve controlling device, and electrical means for opening said contacts after a valve has been operated.
8. The combination with a gas generating apparatus, of a centrifugal pump for ex- 100 hausting gas therefrom, a turbine driving the pump, valve means for regulating the admission of motive fluid to the turbine, and means for maintaining a substantially constant suction on the generating apparatus 105 comprising a device responsive to the pressure of the gas, a device responsive to the speed of the turbine, and connections between said devices and the valve means comprising an electromotive means for actuating the latter and a controller for said electromotive means which is itself controlled by the pressure responsive device and another electromotive means controlled by the movement of a part operated by the first 110 mentioned electromotive means which reacts upon the controller aforesaid to prevent over-actuation of the valve means, so that the devices control the admission of motive fluid to the turbine and thereby regulate the 115 speed of the pump.
9. The combination with a gas generator, of a pump for exhausting the gas therefrom that is located at some distance from said generator, a main leading from the generator to the pump, an engine for driving the pump and regulating means therefor, a 120 device responsive to the variations in the gas 125

pressure located near the generator, an electromotive means for actuating the engine regulating means and controller therefor which is itself controlled by the pressure responsive device, and another electromotive means controlled by the movement of a part operated by the first mentioned electromotive means which reacts upon the controller

aforesaid to prevent overactuation of the engine regulating means.

In witness whereof I have hereunto set my hand this 16th day of May, 1910.

Corrections in Letters Patent No. 1,100,257.

It is hereby certified that in Letters Patent No. 1,100,257, granted June 16, 1914, upon the application of Richard H. Rice, of Lynn, Massachusetts, for an improvement in "Automatic Regulators for Motor-Driven Pumping Apparatus," errors appear in the printed specification requiring correction as follows: Page 4, line 16, strike out the words "to the pump"; same page, line 17, after the word "generator" insert the words *to the pump*; and that the said Letters Patent should be read with these corrections therein that the same may conform to the record of the case in the Patent Office.

Signed and sealed this 14th day of July, A. D., 1914.

[SEAL.]

J. T. NEWTON,

Acting Commissioner of Patents.
